UNITED STATES PATENT OFFICE.

JOHN C. ZIEGLER, OF WICHITA FALLS, TEXAS.

GAS-BURNING STOVE.

1,116,665.

Specification of Letters Patent. Patented Nov. 10, 1914.

Application filed March 8, 1913. Serial No. 752,927.

To all whom it may concern:

Be it known that I, JOHN C. ZIEGLER, residing at Wichita Falls, in the county of Wichita and State of Texas, have invented 5 a new and Improved Gas-Burning Stove, of which the following is a specification.

This invention contemplates certain improvements in that class of stoves more particularly designed for using natural or artificial gas as a fuel and it primarily has for 10 its object to provide a simple and effective means for the utilization of gaseous fuel to the very best of advantage and particularly for effecting a practically perfect intermixing of the oxygen of the air with the 15 carbon, to provide, as it were, for a perfect union of the air and gas for the purpose of producing complete combustion.

With other objects in view that will hereinafter appear, my invention, in its generic 20 nature, comprehends an improved type of stove in which is included an improved construction of the internal or combustion, chamber and so designed whereby to extract 25 the heat units from the gaseous fuel under the most advantageous conditions and also to retard the escape of the same in an efficient manner.

My invention consists in the improved 30 construction and novel arrangement of the parts hereinafter described, specifically pointed out in the appended claim and illustrated in the accompanying drawings, in which:

35 Figure 1 is a perspective view of my improved gas burning stove, parts being broken away to illustrate the internal arrangement. Fig. 2 is a vertical longitudinal section of the same on the line 2—2 on Fig. 3. Fig. 3 is a horizontal section of the 40 same on the line 3—3 on Fig. 2. Fig. 4 is a detail perspective view of the tapering air tube or funnel hereinafter specifically explained. Fig. 5 is a perspective view that 45 illustrates a preferred arrangement of the mixer, the fuel pipe, and the burner.

In the accompanying drawings, I have 50 illustrated a preferred design of an outer drum or casing and a radiator connected therewith, but I desire it understood that the internal construction, the air duct or funnel, and the burner, may be readily modified to suit other shapes of stoves, oval, rectangular or otherwise, without departing 55 from my invention.

In the present showing of my invention,

the drum or outer casing 1, which is an open bottom one and made of any heat radiating metal, is mounted on a cast metal base 2 having legs 3. 4 designates a top or hood that is mounted upon and is attached to the top of the drum 1 in any approved manner. The drum 1 has an opening 6 at the upper or fire chamber portion, normally held closed by a door 7 of suitable shape. 60

8 designates what I term an air funnel or tube and it is also of any suitable heat radiating metal. The lower or base end of the funnel 8 terminates in an annular rim 9 and it is of a diameter to snugly fit inside 70 of the drum and to engage the said open bottom drum and be fastened thereto, in any suitable manner, to provide a perfectly air-tight joint. The upper or small end of the funnel 8 extends to near the top of the 75 drum 1, it terminating just below a burner 11 that is located between the upper end of the funnel 8 and immediately under the stove top. The opening in the restricted end of the air funnel and the space between 80 it and the burner being ample to admit a supply of air for proper combustion.

The burner 11, in the present showing of 85 my invention, is of the horizontal disk type, provided with outlets or jet openings 12 in its periphery. Burner 11 is of sufficient 90 diameter to extend over the outlet 13 from the funnel 8 whereby to serve as a baffle against which the induced air currents are directed (see arrows on Fig. 2), and caused 95 to thoroughly spread to intermix with the flames that discharge from the burner. Burner 11 is mounted on a feed pipe 90 that extends up through the funnel and which also passes down and extends laterally from 95 under the stove and connects with a mixer 14 of any approved type.

The drum 1 has an outlet 14^a and the said outlet, which is located at the bottom of the drum, forms a passage into a radiator 15, 100 consisting of a rectangular chamber that extends vertically at one side of the drum and includes a cover 16 having a collar 17 to receive a pipe 18 of proper diameter and length to create the necessary draft to establish a circulation of air through the combustion chamber. 105

From the foregoing taken in connection 110 with the drawings, the complete construction of my improved type of stove will be readily apparent. The manner in which it operates and its advantages are best ex-

plained as follows: The draft created by the stovepipe attached to the radiator 15 produces a strong induction of air through the funnel coming in direct contact with the flame at the burner, thus supplying additional oxygen to unite with the unconsumed gases at that point. The burner being of a slightly smaller diameter than the outer casing, the burner flame impinges against the 10 casing and spreads into a solid sheet of flame around the entire casing as it is drawn downward by the draft or suction toward the exit "14a." By reason of the manner in which the funnel 8 is mounted within the 15 drum 1, so soon as the heat is developed within the stove, the funnel warms up and begins to radiate heat, and immediately begins to warm the air that passes up through it in proportion to the amount of heat developed within the stove, thus delivering 20 nothing but heated air within the stove and thereby supplying oxygen to the burner under the most favorable conditions. Furthermore, as the mixing tube also soon becomes 25 heated, the temperature of the air and gas passing through it is correspondingly raised. By reason of the peculiar construction of the internal arrangement of my improved stove, none of the products of combustion 30 entering the stove can lower the temperature already developed within the said chamber since the said products having been previously heated, such arrangement of parts, insuring, a combustion of the fuel under 35 most favorable conditions and the creating of an intensely hot and perfectly blue flame. As the passage to the radiator 15 is located at the extreme lower end of the drum 1, and at the most restricted part of the combustion 40 chamber of the stove, a maximum amount of heat units is developed from the burning gases before the said gases escape into the radiator and as the burner is located at the top of the combustion chamber and 45 directly above the funnel 8, it follows that the air column is discharged against the

burner in a manner that insures a quick and effective warming up of the said air column, and as the combustion chamber is of gradually reducing area from the burner downwardly to the outlet to the radiator, the flame and heated air is drawn from the burner, and is caused to rush downwardly toward the exit to the radiator and at the same time is forced against the outer casing or stove drum "1" and against the air funnel 8, thereby causing the drum and the funnel to radiate considerable heat. The bulk of the hot air not thrown off by the stove into the surrounding space, passes into 60 the said radiator, and as the outlet from the said radiator is a restricted one, much of the heat that might otherwise be lost, is retained there and made to radiate into the room. Another feature of my present invention is that as the air fed to the burner through the funnel 8 is drawn up from near the floor, where air is the coldest, a more rapid inflow of air into the stove, and a more uniform circulation is established 65 throughout the room.

What I claim is:

In a gas stove, an outer casing having a closed top, a door in the upper end of said outer casing, an inner casing of funnel 75 shape having its lower or base end open and secured to the lower inner edge of the outer casing, a burner located within the outer casing above the top of the inner casing and adjacent to the top of the inner casing and 80 forming a baffle for the upper or discharge end of said inner casing, means for supporting the lower end of the outer casing and said funnel shaped casing above the floor, a fuel feed pipe that extends through the 85 funnel shaped casing and joins with the burner, and an off-take that opens into the lower end of the outer casing.

JOHN C. ZIEGLER.
